UNITED STATES PATENT OFFICE.

LEOPOLD SCHMIDT, OF DAMASCUS, ILLINOIS.

PLOW.

SPECIFICATION forming part of Letters Patent No. 267,724, dated November 21, 1882.

Application filed April 13, 1882. (No model.)

To all whom it may concern:

Be it known that I, LEOPOLD SCHMIDT, of Damascus, in the county of Stephenson and State of Illinois, have invented a certain new and useful Improvement in Plows; and I do hereby declare that the following is a full, clear, and exact description thereof, reference being had to the accompanying drawings, and to the letters of reference marked thereon, which form a part of this specification.

My invention consists in certain improvements in plows, as hereinafter described and claimed.

In the accompanying drawings, forming a part hereof, Figure 1 is a perspective view of the plow; Fig. 2, a longitudinal section of the plow with the beam and handles broken off, and Fig. 3 a separate view of the reversible parts of the plow detached.

Like letters denote corresponding parts in all three figures.

A represents the beam of the plow, to the rear end of which is attached the rear standard, B, supporting the handles. A front standard, C, is secured to the under side of the beam, at about the same point of attachment of the standard in the ordinary plows now in use. The rear standard, B, is set at its lower end in a horizontal shoe, D, which extends forward to the standard C, and is secured thereto. This shoe D, on its bottom and sides, and the lower portion of the front standard, C, are covered and protected by metal plates *a*, which prevent the wearing of the parts. The plow-frame is rigidly held together by a metal brace, E, which passes down through the beam just in front of the standard C, rearwardly through such standard C, and down through the shoe D. Both of the standards B and C are inclined forward in a downward direction, as shown, to give greater strength and allow for the movement of the reversible parts.

The mold-board, share, point, and colter are made in one piece of metal, of general triangular shape, (shown by F.) This triangular cutting and turning plate is made more or less concave, has its side edges, *b*, turned outwardly and sharpened to form alternately the share and colter, while the point *c* is also sharpened and turned outwardly. The edges *b* extend up to the shoulders *d*, where the triangular plate

is cut away, leaving a central upward projection, *e*, on the rear side of which is secured a plate forming three or more loops or holes, *f*.

G is a horizontal metal shaft, which is turned at its forward end and bolted to the rear side of the plate F, just above its point *e*, at such an angle as to give the triangular plate the right inclination in plowing. This shaft G turns in an opening, *g*, made to receive it in the lower end of the standard C, and passes in rear of such standard above the shoe D and through an eye, *g*, formed in the brace E. The metal covering of the standard C surrounds the shaft-opening *g*. So, it will be seen, both bearings of the shaft are in metal. An eye-plate, *i*, is secured centrally in rear of the standard C, to which plate is hung the hook H, adapted to be shifted to either side of the plow-frame. The forward end of this hook engages with the loops *f* on the projection *e*, and holds the triangular plate on either side of the frame and rigidly at any desired angle of adjustment.

By having three or more loops *f* the plow can be adjusted to cut furrows of greater or less width and depth.

To shift my plow from one side to the other it is only necessary to drive the hook from its loop, swing the reversible parts over to the other side, and again secure the hook.

The shaft is set loosely in its bearings, it being held in place longitudinally as well as laterally by the hook. This allows the triangular cutting and turning plate and its shaft to be readily removed for repairing or sharpening the plow or for replacing the parts when worn out.

What I claim is—

In a reversible plow, the combination of the triangular share F, having extension *e*, and plate provided with three or more loops, *f*, the shaft G, and the hook H on the plow-frame, adapted to engage said loops *f* and be shifted to either side of the frame, substantially as described and shown.

In testimony that I claim the foregoing as my invention I affix my signature in presence of two witnesses.

LEOPOLD SCHMIDT.
